US00D937247S

(12) **United States Design Patent** (10) **Patent No.:** **US D937,247 S**
(45) **Date of Patent:** **** Nov. 30, 2021**

(54) **WALL MOUNT FOR AN AUDIO DEVICE**

(71) Applicant: **Sonos, Inc.**, Santa Barbara, CA (US)

(72) Inventors: **Aki Laine**, Santa Barbara, CA (US);
Edward Mitchell, Thousand Oaks, CA (US); **Philippe Vossel**, Wuppertal (DE)

(73) Assignee: **Sonos, Inc.**, Santa Barbara, CA (US)

(**) Term: **15 Years**

(21) Appl. No.: **29/711,041**

(22) Filed: **Oct. 28, 2019**

Related U.S. Application Data

(63) Continuation of application No. 29/649,645, filed on May 31, 2018, now Pat. No. Des. 870,082.

CLAIM

The ornamental design for a wall mount for an audio device, as shown and described.

DESCRIPTION

FIG. 1 is a perspective view of a wall mount for an audio device, showing our new design;

FIG. 2 is top plan view.

FIG. 3 is a bottom plan view.

FIG. 4 is a front elevation view.

FIG. 5 is a rear elevation view.

FIG. 6 is a first side; and,

FIG. 7 is a second side view.

(Continued)

The features of the wall mount for an audio device shown in broken lines do not form of the claimed design.
